UNITED STATES PATENT OFFICE.

JOHN GABRIELSON AND KNUT KARLSTROM, OF BUFFALO, NEW YORK.

ANTIREFILLABLE BOTTLE.

1,077,060.

Specification of Letters Patent. Patented Oct. 28, 1913.

Application filed September 30, 1912. Serial No. 723,129.

To all whom it may concern:

Be it known that we, JOHN GABRIELSON and KNUT KARLSTROM, subjects of the King of Sweden, residing at Buffalo, in the county 5 of Erie and State of New York, have invented certain new and useful Improvements in Antirefillable Bottles, of which the following is a specification, reference being had therein to the accompanying drawing.

10 This invention relates to antirefillable bottles and the object of our invention is to furnish the neck or mouth of a bottle or other receptacle with a novel check valve that does not interfere with the removal of 15 liquid from the bottle, but prevents the bottle from being filled after the check valve has been placed in position.

Our invention aims to eliminate the nefarious practice of unscrupulous merchants 20 in refilling bottles that once contained a popular brand of liquid, with an inferior liquid, and dispensing the same as the original article. This practice is common among 25 retail liquor dealers and druggists and by providing a bottle with our improved check valve, it is impossible for the bottle to be refilled.

Our invention will be hereinafter specifically described and then claimed and reference will now be had to the drawing, 30 wherein:—

Figure 1 is a vertical sectional view of a portion of a bottle provided with the check valve, Fig. 2 is a side elevation of a detached valve body, Fig. 3 is a top plan of the same, Fig. 4 is a bottom plan of a valve body, Fig. 5 is a side elevation of a detached valvular member, Fig. 6 is a front elevation of the same, Fig. 7 is a side elevation 40 of a detached valve, Fig. 8 is a plan of the valvular member, and Figs. 9 and 10 are horizontal sectional views of the same.

Further describing our invention in detail with reference to the accompanying drawing, wherein like numerals denote corresponding parts throughout: 1 denotes a portion of a bottle or other receptacle having a neck 2 provided with a mouth or rim 3 of greater diameter than the neck 2, there- 50 by forming an annular shoulder 4 within the mouth 3.

5 denotes a cylindrical valve body located within the neck 2 and having the outer end thereof provided with an annular flange 6 that is secured to the shoulder 4 by cement 55 or similar fastening means, whereby the

valve body 5 cannot be removed from the neck 2. The inner end of the valve body 5 is provided with longitudinal equally spaced slots 8 in communication with radially disposed openings 9. The valve body 5, adjacent to the openings 9 has a valve seat 10, and the inner end of said valve body is screw threaded, as at 11 to receive an end plate 12 that has a rectangular opening 13 60 establishing communication between the interior of the bottle and the interior of the valve body 5. The opening 13 also permits of a suitable instrument or key being inserted in the end plate to screw the same in 65 the valve body.

14 denotes a double conical-shaped valve having an intermediate peripheral flange 15 that normally rests upon the valve seat 10 with the inner end of the valve seated. The 75 outer end of the valve 14 has a stem 16.

17 denotes a cylindrical valvular member mounted in the outer end of the valve body 5, the outer end of said member having a head 18 that rests upon the flange 6 of the 80 valve body. The member 17, adjacent to the outer end thereof, has an annular groove 19 and in communication with said groove are angularly disposed ports 20 that establish communication between said groove and the 85 mouth 3. The sides of the member 17, intermediate the ends thereof, are cut away, as at 21 and provided with a transverse opening 22. Arranged in this opening and secured therein by a plug 23 is a locking 90 member having diametrically opposed resilient arms 24. These arms are adapted to engage an annular shoulder 25 provided therefor in the inner wall of the valve body 5. Said arms being easily snapped into position to hold a valvular member and prevent its withdrawal from the valve body 5. The sides of the valvular member have vertical slots 26 and the lower end of said valvular member is reduced and cupped, as at 27 95 to receive the stem 16 of the valve 14. The slots 26 establish communication between the valve body 5 and the ports 20.

There is sufficient play or movement between the valve 14 and the cupped end of the 105 valvular member to permit of the valve 14 opening when the bottle 1 is tilted or inverted. The contents of the bottle can flow into the inner end of said valve body 5, through the valve seat 10, around the valvular member and through the ports 20 thereof, thus permitting of the contents of 110

- the bottle being removed. When the bottle is held in an upright position the valve 14 is seated by gravity, closing the valve seat 10 and preventing liquid that is poured into 5 the mouth 3 from entering the bottle. The shape of the valvular member 17 prevents instruments from being inserted to raise the gravity seated valve 14, consequently the bottle cannot be successfully tampered with.
- 10 In practice, the valve body and the parts held thereby are made of aluminum or a metal not susceptible to a chemical action by the contents of the bottle.
- What we claim is:-
- 15 An anti-refillable bottle comprising the combination with a bottle neck, of a valve body arranged therein and provided intermediate its ends with a partition to consti-

tute a valve seat, a vertically movable flanged stem valve mounted upon said seat, 20 a valvular member fixed within the said valve body and cupped for the reception of the stem of said movable valve, and a plate secured within the inner end of the valve body and provided with a rectangular opening, that portion of the valve body below 25 said partition provided with vertically disposed slots terminating in radially disposed recesses.

In testimony whereof we affix our signatures in the presence of two witnesses.

JOHN GABRIELSON.
KNUT KARLSTROM.
